UNITED STATES PATENT OFFICE

168,726

SIGNALING MITT

Aaron F. Aunspaugh, Houston, Tex.

Application July 1, 1952, Serial No. 20,440

Term of patent 7 years

(Cl. D3—11)

To all whom it may concern:

Be it known that I, Aaron F. Aunspaugh, a citizen of the United States, residing at Houston, in the county of Harris and State of Texas, have invented a new, original, and ornamental Design for a Signaling Mitt, of which the following is a specification, reference being had to the accompanying drawing, forming part thereof.

The single drawing figure is a plan view of the back of a signaling mitt, showing my new design.

The palm side of the mitt is conventionally plain in appearance.

The drawing is lined for color.

I claim:

The ornamental design for a signaling mitt, as shown and described.

AARON F. AUNSPAUGH.
